CLAIM

The ornamental design for a wall mountable back scrubbing brush, as shown and described.

DESCRIPTION

FIG. 1 is a perspective view of a wall mountable back scrubbing brush showing my new design;
FIG. 2 is a front elevational view thereof;
FIG. 3 is a rear elevational view thereof;
FIG. 4 is a side elevational view thereof, the opposite side being a mirror image;
FIG. 5 is a top plan view thereof; and,
FIG. 6 is a bottom view thereof.

FIG. 1

FIG. 2

FIG. 3

FIG. 4

FIG. 5

FIG. 6
